UNITED STATES PATENT OFFICE.

ALFRED C. SANFORD, OF GRANGEVILLE, IDAHO.

THRESHING-MACHINE.

1,241,028.

Specification of Letters Patent. Patented Sept. 25, 1917.

Application filed November 13, 1915. Serial No. 61,286

To all whom it may concern:

Be it known that I, ALFRED C. SANFORD, a citizen of the United States, residing at Grangeville, in the county of Idaho and 5 State of Idaho, have invented certain new and useful Improvements in Threshing-Machines, of which the following is a specification.

This invention relates to improvements in 10 threshing machines for hulling the berries of various kinds of plants.

The principal object of the invention is to provide an improved method and mechanism whereby a differential or variable attritive action will be applied to material acted upon to hull the berries and discharge the same absolutely clean and clear for final separation from the chaff.

More particularly speaking, my invention 20 involves an improved means for gradually advancing the material while the latter is being subjected to a differential or variable attritive action so as to clear the way for a constant feed of material to the machine by 25 reason of the constant discharge therefrom.

In the most specific form of my invention, I employ endless friction belts which are supported by rollers in such a manner as to dispose laps of adjacent belts in abutting 30 relation and in sufficient frictional engagement with each other to relatively tightly compress the heads of the stocks when the latter are advanced between the belts. In order to obtain the threshing or separating 35 action, I advance one belt at a greater speed than the other and I thereby obtain a variable rubbing action which serves to hull the berries without in any way injuring the latter.

40 My improved method and mechanism will be more fully described in connection with the accompanying drawing and will be more particularly pointed out in and by the appended claims.

45 In the drawing:—

Figure 1 is a longitudinal vertical sectional view on line 1—1 of Fig. 3.

Fig. 2 is a view in side elevation.

Fig. 3 is a plan view.

50 Like characters of reference designate similar parts throughout the different figures of the drawing.

In the particular form shown, my improved threshing machine is made up of a 55 frame comprising sides 1 and 2, a bottom

3 and an end 4. In the sides 1 and 2, near the intake or ingress end 5, I journal upper and lower bight rollers 6 and 7. Said rollers are shown as being mounted upon spindles 8 and 9 which are journaled in the sides 1 60 and 2 in such a manner as to rotate about fixed axes. At the egress end 10, of the machine, I provide bight rollers 11 and 12 which are mounted upon spindles 13 and 14, the latter being controlled by tension means, 65 which will be presently described.

About the bight rollers I train belts, preferably of some form of fabric such as canvas, an upper belt being designated as a whole at 15 and a lower belt being designated as a whole at 16. At the ingress end 5, it will be seen that the bight rollers 6 and 7 are in staggered relation, or are off-set sufficiently to cause the bight roller 7 to protrude in subjacent relation with respect to 75 the bight roller 6 thereby providing a convenient intake, as indicated by the arrow. Furthermore, bight roller 11 overhangs bight roller 12 so as to effect a downward discharge of the material, as indicated by 80 the arrow and the egress end 10. Now it will be seen that the adjacent laps 17 and 18, of the belts 15 and 16, are held by the rollers in abutting relation and it will also be noted that the peculiar disposition of the 85 bight rollers is such that their adjacent peripheries are off-set or staggered so as to impart to the abutting laps 17 and 18, a somewhat sinuous contour during their active travel. During the inactive travel of the 90 belts, considering the upper and lower laps 19 and 20, the belts travel in straight lines. Now in order to further enhance frictional engagement of abutting laps 17 and 18, I 95 preferably provide idler rollers, which are also desirably tension rollers, the idle rollers being disposed between the bight rollers and being indicated at 21 and 22. Said idle rollers are mounted upon spindles 23 and 24 and the latter are journaled in bearings 25 100 and 26. Said bearings 25 and 26 are mounted in slots in the sides 1 and 2 and are acted upon by springs 27 and 28, which are interposed between said bearings and suitable abutments 29 and 30.

105 Now it will be seen that the idle and tension rollers 21 and 22 are in such staggered relation with respect to the bight rollers, that they deflect the abutting laps of belts so as to cause said laps to take a sinuous 110

course throughout their travel between said rollers.

The improved tension means herein shown, comprises journal rods 31 and 32, two for each of the spindles 13 and 14, and each journal rod is provided with a boxing formed on its end, as indicated at 33 and 34, in which the ends of the spindles 13 and 14 are journaled. Said tension rods 31 and 32 extend through the end 4, of the machine, and are threaded to receive winged nuts 35 and 36 which may be tightened against the end 4, of the machine to longitudinally displace bight rollers 11 and 12 with respect to bight rollers 6 and 7.

Now it will be seen that the discharge end bight rollers 11 and 12 are not journaled to rotate about fixed axes and that they are capable of yielding movement away from each other, in case of any choking or massing of the material interposed between the adjacent laps 17 and 18.

It will be seen that I have provided tension means acting in the direction of the length of the machine, in the forms of the rods 31 and 32, and also tension means acting transversely of the machine, in the form of spring actuated rollers 21 and 22.

Means is provided for actuating the belt members differentially so as to obtain a high degree of attritive action on the interposed material, and preferably, and at the same time, progressively advance the material from the ingress toward the egress end. In the particular form shown, I drive one of said belts at a higher speed than the other and as illustrated I provide spindle 9 with a relatively large gear 37 which meshes with a relatively small pinion 38 on spindle 8. A pulley 39, actuated by belt 40, serves to drive the belts. The unequal speeds or differential speeds at which the belts are driven, serves to rub the heads, frictionally, as rubbing action might be applied between the two hands, in such a manner as to most efficiently hull the berries.

When I employ fabric belts, such as canvas, I may enhance this rubbing or attritive action by forming ridges on the faces of the belts. In the form shown, I have provided the upper belt with longitudinally disposed ridges which may be formed in any desired manner, said ridges being indicated at 41. On the lower belt I provide transversely disposed ridges 42.

In the present construction, the drive imparted to the belts will be applied to the inactive laps 19 and 20 and reliance is placed upon the tension means, especially the rollers 21 and 22, to keep the abutting laps in proper tension and frictional engagement with each other. However, it will be seen, that if the machine were turned upside down, and the drive were imparted so as to apply tension to the abutting laps 17 and 18, the

necessity for tensioning the rollers 21 and 22 might be avoided.

It is believed that the device of my invention will be fully understood from the foregoing description and while I have herein shown and described one specific form of the method and apparatus, I do not wish to be limited thereto except for such limitations as the claims may import.

I claim—

1. In a threshing machine, endless integral threshing belts of flexible material, belt rollers holding adjacent laps of said belts in continuous pressure engagement throughout their abutting areas with each other to thresh the interposed materials, and means for operating said belts to impart relatively different surface speeds to said adjacent laps, whereby the interposed material will be subjected to sustained attritive action throughout its passage between said adjacent laps, substantially as described.

2. In a threshing machine, endless threshing belts, belt rollers holding adjacent laps of said belts in pressure engagement against each other throughout their abutting areas, and means for operating said belts at different speeds to hull the berries by attrition and gradually advance the material from the point at which it was received between said laps to a point of discharge, substantially as described.

3. In a threshing machine, endless threshing belts, bight rollers supporting said belts with laps of the latter in abutting relation to receive the stalks therebetween, idler rollers engaging said abutting laps to cause the latter to assume a sinuous course during their travel and throughout their abutting areas, and means for driving one of said belts at a greater speed than the other, substantially as described.

4. In a threshing machine, endless threshing belts, upper bight rollers for one belt, lower bight rollers for the other belt arranged with respect to the upper bight rollers to dispose adjacent laps of the belts in abutting relation, said upper and lower bight rollers having their peripheries in staggered relation, idler rollers holding said abutting laps in pressure engagement with peripheries of said idler rollers being in staggered relation to cause the abutting laps to take a sinuous course, tension means for the bight rollers of each belt, and means for driving said belts at unequal speeds to attritively hull the berries, substantially as described.

5. In a threshing machine, endless belts, rollers for supporting said belts with adjacent laps in abutting relation, one of said belts having longitudinally disposed attritive ridges and the other of said belts having transversely disposed attritive ridges, and means for driving said belts at unequal

speeds to hull the berries by attrition, substantially as described.

6. In a threshing machine, endless flexible threshing belts of homogeneous material, rollers for supporting said belts with adjacent laps in abutting relation, said belts having attritive ridges and the remainder of said belts being continuously smooth, and means for driving said belts at unequal speeds, substantially as described.

7. In a threshing machine, endless threshing belts, eight rollers for supporting said belts with adjacent laps thereof in abutting relation to receive the stalks therebetween, and belt tensioning idler rollers engaging the butts of the abutting laps to hold the same in pressure engagement, and means for driving said belts at unequal speeds to hull the berries by attrition, substantially as described.

8. The herein described method of threshing grain, which consists, in progressively advancing the stalks and heads, and in applying sustained friction continuously there- 25 to during such advancing movement to hull the berries, substantially as described.

9. In a threshing machine, endless threshing belts, eight rollers supporting said belts with adjacent laps in abutting relation, devices engaging said abutting laps to hold the same in continuous pressure engagement with respect to each other, and means for driving said belts at different speeds to attritively hull the berries, substantially as de- 35 scribed.

10. In a threshing machine, coacting elongated flexible threshing members for threshing action on material therebetween, means applying endwise tension to said members, 40 means acting on said members transversely

of their length in opposition to said first mentioned means to urge said members into sustained engagement with each other throughout their coacting areas, and mechanism imparting differential motion to said 45 members, substantially as described.

11. In a threshing machine, coacting elongated flexible threshing members for threshing action on the material therebetween, means applying endwise tension to said members, means acting on said members transversely of their length in opposition to said first mentioned means to urge said members into sustained engagement with each other throughout their coacting 55 areas and causing said members to take a sinuous form and mechanism imparting differential motion to said members, substantially as described.

12. In a threshing machine, coacting elongated flexible threshing members for threshing action on material therebetween, means urging said members into continuous and sustained engagement from end to end 65 and between their ends and causing said abutting members to take a sinuous form, means applying tension endwise of said members and coacting with said first named means to maintain sustained frictional engagement between said members throughout 70 their length, and mechanism imparting differential motion to said members, substantially as described.

In testimony whereof I affix my signature in the presence of two witnesses.

ALFRED C. SANFORD.
